his Atty's

UNITED STATES PATENT OFFICE.

JOHN B. ODELL, OF CHICAGO, ILLINOIS.

ANNUNCIATOR FOR TELEPHONE-SIGNALS.

SPECIFICATION forming part of Letters Patent No. 250,384, dated December 6, 1881.

Application filed August 4, 1881. (No model.)

To all whom it may concern:

Be it known that I, JOHN B. ODELL, of Chicago, Cook county, State of Illinois, have invented certain new and useful Improvements 5 in Annunciators for Telephone-Signals, of which the following is a specification.

My invention relates to improvements in annunciator-drops for telephone-signals; and the same consists in providing the hinged drop 10 with an arm, which operates when the drop falls to at once automatically close the ringer-circuit and shunt or short-circuit the coils of the annunciator, so that the bell may ring until the operator comes to the instrument, when 15 by turning the handle of the contact-strip he can break the ringer-circuit and stop the ringing of the bell, said contact-strip being pushed back into position again by raising the drop.

My invention will be more fully understood 20 by reference to the accompanying drawings, which form a part of this specification, and in which similar letters of reference indicate like parts.

In said drawings, Figure 1 is a side elevation 25 of a device embodying my invention; and Fig. 2 is a plan view of the same, the magnet and armature of the annunciator being removed.

In the drawings, A represents the frame piece or plate, to which the hinged drop B is 30 pivoted.

C are the coils of the electro-magnet, and D the armature, pivoted to the frame at d.

a is the adjustable screw-stop for the armature, and b is the catch-bar, provided with 35 notches b' for the drop. The catch-bar is pivoted to the slotted post b² on the armature, and may be adjusted in respect to the drop by the adjusting-screw b³ in the slotted post b⁴ on the end of the armature, said screw pressing 40 the catch-bar against a spring, b⁵, which is secured to the post b². The catch-bar is provided with a notch, b', at each end, so that by reversing its ends the same will operate to release the drop when the armature is operated 45 by a closed circuit as well as by an open circuit.

c c' are binding-posts, to which the main or line wires c² c² are connected, and also the wires c³ c³, leading to the coils C C.

50 c⁴ is a contact-strip secured to the binding-

post c, the end of which projects under the end of the corresponding contact-strip c⁵, secured to the binding-post c'.

c⁶ c⁷ are similar contact-strips secured to the binding posts c⁸ c⁹, to which the wires of the 55 ringer-circuit c¹⁰ c¹¹ are connected.

a² is an arm projecting from the drop B, which operates when the drop falls to press the ends of the contact-strips c⁴ c⁵ together, and also the ends of the contact-strips c⁶ and c⁷, 60 thus at the same time shunting or short-circuiting the coils C C and closing the ringer-circuit. The contact-strip c⁶ turns on the binding-post c⁸ as a pivot, and is provided with a handle or crank-arm, c¹², by which the operator, when he comes to the instrument, may swing said contact-strip from underneath the strip c⁷ and break the ringer-circuit, thus stopping the ringing of the bell. When the drop is raised or restored to its position under the 65 catch-bar a projection, c¹³, on said contact-strip c⁶, striking against the drop, causes the contact-strip to swing back into its original position under the contact-strip c⁷, so that when the drop again falls the connection between c⁶ and 70 c⁷ will be made the same as before.

The numbers on the drop-plate B indicate the number of the telephone-station from which the signal comes.

By use of my invention the first impulse giving 80 the signal at once automatically shunts the annunciator-coils and sets in operation the continuously-ringing bell, which rings until the operator's attention is called and he turns the handle c¹², and when the drop is raised the 85 short circuit, which shunts the annunciator, is automatically broken, and the spring c⁶, which forms part of the ringer-circuit, is automatically pushed back in place to form a connection with c⁷ the next time the drop falls. 90

It should be observed that the spring contact-strips c⁴ and c⁶ should be so adjusted and arranged that the weight of the drop will force them against the strips c⁵ and c⁷, respectively, to form the connections, while when the drop 95 is raised they spring back to break the connection.

If preferred, the strips c⁴ and c⁶, instead of operating as springs, may be secured loosely 100 to the binding-posts, so as to operate by their

gravity to break the connection when the drop is raised.

I claim—

1. In a telephone-annunciator, the combination of frame A, drop B, hinged thereto and provided with arm a^2 , pivoted armature D, provided with adjustable catch-bar b, contact strips c^4 c^5 , forming part of a short circuit to shunt the coils of the annunciator, and contact strips c^6 c^7 , forming part of the ringer-circuit, said contact-strips being operated by said arm a^2 to make and break the circuits, substantially as specified.

2. The combination of drop B, provided with arm a^2 , contact-strip c^6 , being part of the ringer-circuit, provided with a handle, whereby the operator may break the circuit, and means whereby the said strip is restored to its normal position by raising the drop, said strip being operated by said arm a^2 to make the connection when the drop falls, substantially as specified. 15 20

JOHN B. ODELL.
